UNITED STATES PATENT OFFICE.

JOHN KELLEY, OF EAST ST. LOUIS, ILLINOIS.

METALLIC ROD-PACKING.

SPECIFICATION forming part of Letters Patent No. 561,794, dated June 9, 1896.

Application filed June 17, 1895. Serial No. 553,040. (No model.)

To all whom it may concern:

Be it known that I, JOHN KELLEY, of the city of East St. Louis, St. Clair county, State of Illinois, have invented certain new and useful Improvements in Metallic Rod-Pack-
5 ing, of which the following is a full, clear, and exact description, reference being had to the accompanying drawings, forming a part hereof.

10 My invention relates to an improved metallic rod-packing; and it consists in the novel construction, combination, and arrangement of parts hereinafter described and claimed.

15 In the drawings, Figure 1 is a longitudinal sectional view of a piston-rod stuffing-box, the same having my improved packing applied thereto. Fig. 2 is an edge elevation of one of the expandible rings of which I make use in carrying out my invention. Fig. 3 is
20 a top plan view thereof. Fig. 4 is a horizontal sectional view taken approximately on the indicated line 4-4 of Fig. 2.

25 Referring by numerals to the accompanying drawings, 1 indicates an ordinary stuffing-box, through which the piston-rod 2 reciprocates, and said stuffing-box is provided with the usual gland 3, the same being held to the stuffing-box by bolts 4. The annular space between the end of the gland 3 and the
30 head of the engine or pump cylinder within the stuffing-box 1 is occupied by my improved metallic packing, and said packing, as shown, comprises an annular casing 5, having an open end, and the inner face of said annular casing, adjacent said open end, is screw-threaded, as indicated by 6. The opposite end of said cas-
35 ing is closed, with the exception of an aperture 7 of the same diameter as is the aperture through the head of the engine or pump
40 cylinder through which the piston-rod passes. This casing 5 is intended to be located di-
rectly against the head of the pump-cylinder, and a soft metallic ring 8 is located in the outer edge of the face of said casing 5.

45 9 indicates a second casing having an open end interiorly screw-threaded, as indicated by 10, and provided on its opposite end with a head 11, through which is formed an aperture 12 of the same diameter as is the aperture 7 in the casing 5. Said head 11 is pro-
50 vided with a projecting portion 13, that is

exteriorly screw-threaded, and the diameter of said projecting portion 13 is such that it may be readily screwed into the open end of the casing 5, the screw-threads on said pro-
jecting portion 13 engaging in the screw-
threads 6 in said casing 5. There may be a
series of these casings 9, it only being essen-
tial to partially fill the stuffing-box 1; but I
find that one of the casings 5 and one of the
casings 9 are sufficient in the stuffing-boxes
ordinarily located upon engine and pump
cylinders.

14 indicates an annular cap-plate provided with a centrally-arranged aperture 15, and 65 also provided with an exteriorly-screw-
threaded head 16, that is of such a diameter as that it will readily pass into the screw-
threaded end of the casing 9.

70 The metallic packing-rings comprise seg-
ments 17, but slightly less than true semicircles, and said rings are slightly less in diameter than are the interior diameters of the casings 5 and 9. Formed in the peripheries
75 of the segments comprising these rings are
grooves 18, the same being semicircular in
cross-section.

77 Formed in the bodies of the segments 17
and extending inwardly from the grooves 18
and at points on the segments opposite one 80
another are recesses 19.

85 Springs 20 comprise single lengths of resili-
ent metallic wire bent into semicircular form
in order to fit in the semicircular grooves 18.
The ends of these springs 20 are bent in-
wardly toward one another, and said ends en-
gage in the recesses 19, formed in the seg-
ments 17. The normal tendency of these
springs 20 is to force the ends of the segments
17 against one another, thereby slightly de-
90 creasing the diameters of the apertures
through the rings.

95 Formed in the meeting ends of the seg-
ments 17 and directly opposite one another
are rectangular recesses 21, in which are lo-
cated plates 22. It is intended that there be
a pair of these rings located in each one of the
casings 5 and 9. To break joints between the
ends of the segments forming the pairs of rings
and to cause each pair of rings to move to-
gether, in one ring of each pair I locate a dowel-
pin 23, and in the mating ring of the pair is

formed a recess, such as 24, in which this dowel-pin engages. By properly locating these dowel-pins and recesses the meeting ends of the segments of the mating ring to the one shown in Fig. 3 would occupy approximate positions, as indicated by parallel dotted lines in Fig. 3. The rings are of such thickness as that when in pairs they are located in the casings they will completely occupy the spaces between the ends of said casings and the ends of the opposite casings or cap.

The casings are made in sections in order that they may be easily applied to or removed from the rods and stuffing-boxes without necessitating the detaching of the rod from the cross-head.

The casings with their rings occupying the space within the stuffing-box do not take up any more room than is ordinarily occupied by the packings now in use.

When the casings containing the rings are located within the stuffing-box and upon the piston-rod and said piston-rod is reciprocated, the tendency of the springs 20 is to force the meeting ends of the segments of the rings toward one another, thereby causing the inner faces of said rings to engage very tightly upon the surface of the piston-rod. As there are a series of these rings, any direct blowing through or leakage of steam between said rings and the piston-rod is impossible. A certain amount of steam will necessarily pass between the ring nearest the head of the cylinder and the inner wall of each casing to the space between the peripheries of the first series of rings and the inner face of the first casing; but said steam will be prevented from further escape by reason of the plates 22 cutting off its passage into whatever space there 40 might be between the first set of rings and the piston-rod.

By constructing the segments 17 of the rings of suitable material the use and necessity of lubricating substances are dispensed with.

45 Thus will be seen how I have constructed a metallic rod-packing that is perfectly water and steam tight, is easily and quickly placed

in or removed from position, is very compact, and is extremely durable and efficient.

I claim—

The combination, with the stuffing-box 4, of metallic packing for piston-rods comprising the annular casing 5 having the interiorly-screw-threaded end 6 and the aperture 7 in the opposite end, said casing being located directly against the head of the cylinder, the soft metallic ring 8 the body of which is square or rectangular in cross-section, located in the outer edge of the face of said casing 5 and arranged and designed to be pressed into the corner formed by the juncture of the wall of the stuffing-box with the head of the said cylinder, the casing 9 having the interiorly-screw-threaded end 10 and provided on its opposite end with the head 11, said head having the aperture 12 and the projecting portion 13 which is exteriorly screw-threaded for insertion in the open end of the casing 5, the annular cap-plate 14, having the aperture 15 and the exteriorly-screw-threaded head 16 for insertion into the screw-threaded end of the casing 9, the metallic packing-rings consisting of the segments 17 having the grooves 18 which are semicircular in cross-section and the recesses 19 at points on said segments opposite one another, the springs 20 consisting of resilient metallic wire bent into semicircular form to fit in the semicircular grooves 18 and having the ends bent inwardly toward one another said ends to engage in the recesses 19, the plates 22 located in the rectangular recesses 21 formed in the meeting ends of the segments 17, the dowel-pins 23 fixed in one of said metallic rings to engage in recesses 24 in the mating ring, the object being to break joints between the said rings which are arranged side by side to fill said casing 5, substantially as and for the purposes stated.

In testimony whereof I affix my signature in presence of two witnesses.

JOHN KELLEY.

Witnesses:

EDWARD E. LONGAN,
MAUD GRIFFIN.
